UNITED STATES PATENT OFFICE.

GEORGE R. OTT, OF BALTIMORE, MARYLAND, AND DAVID P. CORDRAY, OF WEST POINT, NEW YORK.

STOCK-CAR.

SPECIFICATION forming part of Letters Patent No. 357,535, dated February 8, 1887.

Application filed October 25, 1886. Serial No. 217,157. (No model.)

To all whom it may concern:

Be it known that we, GEORGE R. OTT, of Baltimore, in the State of Maryland, and DAVID P. CORDRAY, of West Point, in the county 5 of Orange and State of New York, citizens of the United States, have invented certain new and useful Improvements in Stock-Cars; and we do hereby declare the following to be a full, clear, and exact description of the invention, such as will enable others skilled in the art to which it appertains to make and use the same.

Our invention relates to that class of stock-cars which are provided with a movable deck 15 to form either a two or one compartment car. Cars of this description have been provided with various means for raising and lowering the decks, and no claim is made to the broad idea of such a construction.

20 The object of our invention is to construct a car of that character in such manner that all the elements necessary to successful operation, safety, and strength will be provided for, and at the same time be made and put together without much additional expense over the cost of the ordinary car.

To that end the nature of the invention consists of constructions and combinations, all as will hereinafter be set forth in the specification, and pointed out in the claims, reference being had to the accompanying drawings, in which—

Figure 1 represents a side elevation of a stock-car; Fig. 2, a longitudinal section showing the movable deck lowered to the position 35 when small stock is to be transported; Fig. 3, an end elevation showing the position of the hoisting mechanism; Fig. 4, a transverse section showing the movable deck in its lower position; Fig. 5, a similar section showing the movable deck raised to its upper position; Fig. 6, a detail on an enlarged scale to show part of the door-jambs and the bar across the doorway; Fig. 7, an end view of one side of 40 the door-jamb to show the receiving-socket for the bar, which is shown in cross-section; Fig. 8, a detail showing the hoisting mechanism in enlarged side elevation; Fig. 9, a de-

tail showing the hoisting mechanism in end elevation, the hand-wheel being partly broken 50 away to show the parts more clearly; Fig. 10, an enlarged side elevation, looking from the inside of the car, to show the hoisting-chain, the guide, and automatic catch; Fig. 11, a section taken through one of the slots to show 55 the relative positions of the parts shown in Fig. 10, and Fig. 12 a detail showing one of the guides in cross-section.

A represents the car-body, and B the movable deck. The body is formed in the usual 60 way, and has in its sides at intervals vertical slots A', which extend from the longitudinal top beams, A², to the middle beam, A³. This beam A³ is formed by attaching a board of extra thickness to the side of the car, and preferably against one of the side slats, to give 65 greater strength. Metal guides A⁴, having an outer flange, a, are placed in the slots to prevent wear upon the wooden walls of the slots by the ends of the joists B' of the movable 70 deck B. These joists project into the slots, and are provided at their ends with wrought-iron plates B², bolted on the sides thereof. Upon the outer ends of these plates are formed lips b², which project laterally over the flanges 75 a of the guides A⁴, Fig. 12, and prevent the movable deck from swinging or having a lateral motion.

The deck B is formed of any suitable material, but is preferably made of boards resting upon the joists B'. The boards are tongued and grooved together to prevent liquid or other material passing between them and dropping on the animals below. If desired, the edges of the deck may be provided with suitable 85 devices to prevent the liquid matters from running over the edges and marring the appearance of the stock below. Each end of the joists B' is provided with an eyebolt, b', for a hoisting-chain, C, to be attached to. These 90 chains extend up the side of the car to and pass over the sheaves C', secured to the top beam, A². From the sheaves the chains are passed to and secured to spools D' by means of pins or bolts d'. Two chains are attached 95 to each of these spools D', which, to prevent

the chains from interfering with each other when wound thereon, are provided with helical grooves d^2 and d^3 , running in opposite directions from the starting point or space d^4 .

- 5 The spools are keyed or otherwise attached to a longitudinal shaft, D^2 , journaled at suitable points in bearings d , attached to the rafters of the car. This shaft projects at one end outside of the car, and has upon this projecting end a worm-wheel, D^3 , meshing with a worm-shaft, D^4 , having bearings d^5 , attached to the protecting-box D^5 .

The inner end of the worm-shaft D^4 is provided with a miter-wheel, d^6 , which meshes with a miter-wheel, d^7 , on the shaft d^8 , that is journaled in the protecting-box D^5 , attached to the end of the car, and covers the gearing just described to prevent snow and dirt from interfering with the movement of said parts.

- 15 20 Upon the outer end of shaft d^8 is fixed a hand-wheel, D^6 , by means of which motion is imparted to the gearing to raise or lower the deck by winding or unwinding the chains upon the spools. When the deck is lowered to the position shown in Fig. 4, the chains are relieved of the weight of said deck, as the joists B rest upon the bottom of the guide-plates A^4 . To relieve the chains of the weight of the deck, when the latter is raised to form a single-compartment car, stops a^4 are provided. These stops a^4 are pivoted in an extension, a^5 (see Fig. 10, dotted lines,) of the guides A' , and project across the slot A' to the opposite wall of the metal guides A' in an upward and inclined position, so that as the deck is raised the joists B will force them to one side, and after the joists pass they will automatically fall in the position shown in Fig. 10, to be ready to receive the joists when the deck is lowered to relieve the chains of the strain. These stops also prevent the deck from being accidentally lowered or falling when the car is used to convey large animals or other freight.

The door-jambs A^5 and A^6 are respectively provided with recesses a^3 and a^6 for the removable bar E . The recess a^3 is provided with a plate, a^7 , having a curved back, a^8 , to allow the bar to be readily removed when not held in place by a pin, a^9 , which passes through holes 50 in the plate a^7 .

In one end of the car is formed a door, F , through which lumber, rails, and other long merchandise can be inserted when their length is such that the side doors cannot be used.

- 55 If desired, the shaft D^2 may be made square, as also the cored holes in the worm-wheel, gearing, and spools, so that the entire lifting arrangement can be put up as it comes from the foundry, with the exception of a few pin-holes, which are necessary.

The operation of the device is as follows: If it be desired to use the car for carrying sheep or other small stock, the deck is lowered to the position shown in Fig. 1 by raising the joists

B' from the automatic stops a^4 , which are then thrown back to permit the deck to sink to the desired position by gravity, a man being at the hand-wheel D^6 to prevent it from falling too rapidly and injuring the parts. To raise the deck to the position shown in Fig. 5, the stops a^4 are placed in the position shown in Fig. 10, and the operator at the hand-wheel turns and communicates motion by it, and by means of the miter-wheels, worm-shaft, and worm-wheel, to the longitudinal shaft and the 75 spools which wind the chains thereon and raise the deck to the highest point. As the ends of joists B' pass upwardly they lift the stops a^4 , which automatically return to their normal position after the joists have passed, 80 and the operator lowers the deck until the joists rest upon the upper ends of the stops.

What we claim as new is—

1. In a stock-car, the combination of the body having vertical slots, a movable deck 85 having transverse joists extending through said slots and provided with laterally-projecting lips on the outer ends to prevent lateral motion of the deck, and means, substantially as described, for raising and lowering the deck, 90 as set forth.

2. In a stock-car, the combination of a body having vertical slots provided with flanged metal guides, the movable deck having transverse joists extending through said slots and 95 provided with laterally-projecting lips, and means, substantially as described, for raising and lowering the deck, as set forth.

3. In a stock-car, the combination of a body having vertical slots provided with automatic 100 stops, a movable deck having transverse joists projecting through said slots, and means, substantially as described, for raising and lowering said deck.

4. In a stock-car, the combination of the 105 body, a movable deck having chains attached thereto, and a shaft having spools to which the chains are attached and provided with diverging helical grooves, substantially as described.

5. In a stock-car, the combination of the body having sheaves attached to the sides, a movable deck having chains which pass over said sheaves, and a shaft having pulleys to which the chains are attached and provided 115 with diverging helical grooves, substantially as described.

6. In a stock-car, the combination of a body, a movable deck having chains by which it is raised and lowered, a shaft having pulleys for 120 said chains and a worm-wheel at the end, a worm-shaft having a miter-wheel, and a counter-shaft having a miter-wheel meshing with the worm-shaft's miter-wheel, and having a hand-wheel for imparting motion to said gearing, substantially as described.

7. In a stock-car, the combination of a body having a side-door bar provided with notches,

and a movable deck having transverse joists which rest in said notches when the deck is lowered, substantially as described.

8. In a stock-car, the combination of a body having vertical slots, metal guide-plates in said slots and having an automatic stop attached thereto, a movable deck having transverse joists projecting through said slots, and means, substantially as described, for raising and lowering said deck, as set forth.

In testimony whereof we affix our signatures in presence of two witnesses.
